DESIGN FOR A BAG

Alfred Merwin Hickman, Paterson, and Gladys
Byrd Shield, Ridgewood, N. J.

Application February 12, 1942, Serial No. 105,780

Term of patent 3½ years

To all whom it may concern:

Be it known that we, Alfred Merwin Hickman, a citizen of the United States, residing at Paterson, in the county of Passaic and State of New Jersey, and Gladys Byrd Shield, a citizen of the United States, residing at Ridgewood, in the county of Bergen and State of New Jersey, have invented a new, original, and ornamental Design for a Bag, of which the following is a specification, reference being had to the accompanying drawing forming a part thereof.

The figure is a perspective view of a bag showing my new design.

The side of the bag not shown is a substantial duplicate of that illustrated.

The characterizing features of our design reside in the combination on a bag of the configuration shown, of the specific strap and bar handles illustrated.

We claim:

The ornamental design for a bag, substantially as shown and described.

ALFRED MERWIN HICKMAN,
GLADYS BYRD SHIELD.
